JOSEPH C. DONNELLY, OF BARBERTON, OHIO, ASSIGNOR TO THE DIAMOND MATCH COMPANY, OF CHICAGO, ILLINOIS, A CORPORATION OF ILLINOIS.

DISCHARGING MECHANISM FOR MATCH-MACHINES.

1,168,863.

Specification of Letters Patent.

Patented Jan. 18, 1916.

Application filed April 28, 1914. Serial No. 834,904.

To all whom it may concern:

Be it known that I, JOSEPH C. DONNELLY, a citizen of the United States, and resident of Barberton, in the county of Summit and State of Ohio, have invented certain new and useful Improvements in Discharging Mechanism for Match-Machines, of which the following is a specification.

This invention relates to match-discharging mechanism for match machines, having reference more particularly to that class of discharging mechanism wherein a punch bearing head is mounted and arranged to reciprocate in relation to the successive rows 15 of match-holding perforations of a traveling match carrier.

The object of the invention is to provide mechanism of simple and efficient construction whereby the punch head shall be maintained in a straight path, at right angles to that of the match carrier; whereby access 20 to the punches, for renewal or repair, may be readily had, and whereby also access to the portion of the carrier in the region of 25 the punch head may be as readily effected.

The invention consists, primarily, in a match-discharge mechanism comprising a reciprocating carriage, a punch head pivotally mounted thereon, and locking devices 30 for said head, the whole being so constructed and arranged that the punch head can be readily locked with its punches in operative position relatively to the match carrier, or can be as readily unlocked to permit such 35 head and its punches to be swung away from the said carrier.

The invention also comprises features of construction and combinations of parts which will be hereinafter described and 40 claimed.

In the drawings Figure 1 is a plan view of mechanism embodying my invention, only so much of a match making machine being shown as is necessary to illustrate the 45 invention. Fig. 2 is a longitudinal vertical section partly in elevation, as on the line 2—2 of Fig. 1. Fig. 3 is a front view of the punch head and adjuncts. Fig. 4 is a vertical section, enlarged, of the punch head and 50 its carriage on a plane through one of the locking pins, as on the line 4—4 of Fig. 3. Fig. 5 is a detail, in perspective, of the locking pins for the punch head and the operating devices for said pins.

55 10 designates a part of the main frame of

a match making machine, and 11 a part of the endless match carrier. This carrier in the form illustrated comprises plates provided with rows of perforations into which the ends of the match splints are forcibly inserted and thereby rigidly held, the plates being intermittently moved by suitable gearing in a manner to advance the rows of perforations, with their matches, successively to the horizontal path of a corresponding row 65 of reciprocating ejecting punches 12.

The actuating mechanism for the match carrier includes a pair of gear wheels 13 which mesh with gear teeth along the outer edges of the plates, said wheels being borne 70 by an intermittently driven shaft 14 having its bearings in suitably-disposed boxes on the main frame. The longitudinal edges of the carrier, adjacent the ejecting punches, are supported and guided by vertically-disposed guide members 15 which are adjustably secured to the main-frame by bolt and slot connections 15'.

According to my invention the row of 80 punches is carried by a head 16 which is hingedly connected with a reciprocating carriage 17, and means are provided whereby the said head can be readily locked with its punches in operative position, or can be as readily unlocked in order to permit 85 the punch head and its punches to be swung away from the match carrier, as desired.

The carriage in its preferred construction 90 includes a horizontally disposed body provided at its ends with guide ribs 18 which are slidingly fitted to guide-ways 19 in a stationary bed-plate 20 on the supporting frame, directly in rear of the match carrier, so that the carriage may be reciprocated at 95 right angles to the latter. The carriage body is provided with rearwardly-extending lugs 21 which are connected by rods 22 with rocker-arms 23 on a rock-shaft 24 journaled in boxes on the main frame. This shaft is 100 equipped with a lever 25 which is operatively connected with and timely oscillated by a suitable cam on the main shaft of the match machine, as usual.

The punch head 16 in its preferred construction 105 includes a substantially L-shaped body which when in active position overhangs the shaft 14 and rests upon a wall on the body carriage 17. The row of punches is mounted in an angle bar 26 which is de- 110

tachably secured to the forward depending portion of the head by screws 27 or other suitable means, the punches being properly spaced and positioned to register with succeeding rows of perforations of the match carrier. The body of the punch-head is provided with rearwardly-extending arms 28 which preferably merge with strengthening ribs on the body. These arms are hingedly 5 connected to suitably-disposed bearing lugs 29 on the rearward part of the carriage so that the said head, with its row of forwardly projecting punches, may be bodily swung upward and rearward when the carriage is retracted and the punches clear of the match carrier, and thus permit ready access to the rearward portion of said carrier at the discharge station or to the punches, as occasion may require. In Fig. 3 10 the punch head is indicated by dotted lines as swung rearward. The head is preferably furnished on its upper side with a suitable handle 30.

The forward wall of the punch head is 25 provided with apertured depending lugs 31 which, when the head is in down or active position, are seated in vertical recesses in the contiguous end of the carriage body with the apertures 32 of the lugs in registry 30 with transverse perforations 33 in said body. Slidingly fitted to these perforations are pins 34, which are movable into or out 35 of the apertures of the lugs so as to lock or release the forward portion of the head as desired. These pins thus constitute bolts which by virtue of their close relation to the forward end of the head insure the firm and rigid locking of the punch-bearing portion of the latter to the carriage, which carriage and punch head are therefore reciprocated as a unit in a straight path at right angles to that of the match carrier.

Mounted to slide horizontally in a guideway 35 at the rear of the carriage is a bar 45 36 which has formed on its under side at its respective ends inclined cam ribs 37 which enter corresponding cam grooves 38 in enlarged outer ends of the pins 34, whereby longitudinal movement of the bar 36 in one 50 direction retracts the pins from the apertured lugs 31 to unlock the head, and similar movement of the bar in the opposite direction projects the pins into the lugs to lock the head. In the upper face of the slide bar 55 55 are gear teeth 39 with which mesh the toothed segmental portion 40 of a handle 41 which is pivoted by means of a stud to a lug 42 on the carriage. Thus by swinging the handle to the right or left the slide bar is 60 positively moved to effect either the retraction or the projection of the locking pins

as desired. The lock controlling handle being located at the rear of the carriage is readily accessible to the attendant.

My invention is not limited to the details 65 of construction herein shown and described as the structure may be modified without departing from the spirit of the invention.

I claim—

1. In discharge mechanism for match machines, the combination with a progressively movable carrier for successive rows of matches, of a carriage reciprocative at right angles to the path of travel of said carrier, means for actuating said carriage, a match-ejecting punch head hingedly mounted on said carriage and movable therewith toward and from the match carrier, and means for locking said head in operative position on the carriage. 70

2. In discharge mechanism for match machines, the combination with a progressively movable carrier for successive rows of matches, of a carriage reciprocative at right angles to the path of travel of said carrier, 75 means for actuating said carriage, a head hingedly mounted at its rearward end on said carriage and movable therewith toward and from the match carrier, match-ejecting punches projecting outward from the forward part of the said head, and means for locking the forward part of the head to the carriage. 80

3. In discharge mechanism for match machines, a reciprocating carriage, a head 95 hingedly mounted at its rearward end on said carriage and having at its forward end locking members, punches projecting outward from the forward part of said head, locking-pins extending from front to rear 100 of said carriage adapted to be engaged with and disengaged from said locking members, and means for actuating said pins.

4. In discharge mechanism for match machines, a reciprocating carriage, a head 105 hingedly mounted at its rearward end on said carriage and having at its forward end locking members, locking pins extending from front to rear of said carriage adapted to be engaged with and disengaged from said locking members, a gear rack bar having a cam connection with said pins, and a manually-operated gear element engaged with said bar. 110

Signed at Barberton, in the county of 115 Summit and State of Ohio this 23rd day of April A. D. 1914.

JOSEPH C. DONNELLY.
